US00D882038S

(12) United States Design Patent (10) Patent No.: US D882,038 S
(45) Date of Patent: * Apr. 21, 2020

(54) CAPSULE WATER FILTERS

(71) Applicant: FRANKE TECHNOLOGY AND TRADEMARK LTD, Hergiswil (CH)

(72) Inventor: Michael Loepfe, Zürich (CH)

(73) Assignee: Franke Technology and Trademark Ltd, Hergiswil (CH)

() Term: 15 Years

(21) Appl. No.: 35/506,622

(22) Filed: Aug. 16, 2018

(80) Hague Agreement Data

Int. Filing Date: Aug. 16, 2018

Int. Reg. No.: DM/103096

Int. Reg. Date: Aug. 16, 2018

Int. Reg. Pub. Date: Feb. 22, 2019
